UNITED STATES PATENT OFFICE

2,280,239

SANITARY PRESERVING CAN OR CONTAINER AND THE MAKING OF IT

Heinrich Karl, Jersey City, N. J.

Application July 15, 1937, Serial No. 153,747

5 Claims. (Cl. 229—3.5)

The aforesaid improvements refer chiefly to the imprinted coat or coatings of the interior sides of the cans or containers including those of the top and bottoms and of additional linings and of covering means that are placed between the contents of the can and the top and bottom thereof, respectively.

These cans or containers refer chiefly to the kind that are made of other materials than sheet metal or that have at least the main parts thereof made of a non-metallic material. Such non-metallic materials include chiefly fibrous sheet materials in blank form, such as, paper, card board, but others may be included, as, for instance, impregnated cloth, cellulose materials, an inferior kind of nitro cellulose such as pyroxylin and others.

More particularly the coat or coatings of the innermost side of the can body are made in such way and are of such character that they can be inspected easily and even tested before the whole blank (or several, if the can is constituted by more than one blank) is, or are, wound into the can body.

The inner blanks form then the parts of at least the inner walls of the can or container body and of the top and bottom.

It has been proposed already to coat the interior side of a finished vessel or can by painting or by pouring in the lacquer or other material that is to form the interior coat and to let drain out the surplus material. The coatings made in this way would not only be far costlier but they could not be inspected so thoroughly and easy besides that faults could not be repaired in such simple and thorough way as it is possible with the present scheme.

According to the scheme of this invention the coat or coatings for the interior side of the can are preferably made right on the large sheet from which the blanks will be cut that have to form the interior side of the can or container and also the exterior side thereof. The blanks may, however, form only the interior side of the can such as do linings.

The coat or coatings may also be applied to the already cut blanks before they are wound up or assembled and this is especially the case when it deals with a can or container that will have an inner and an outer wall and a packing therebetween with reinforcing strips of steel or wires or fibres.

This permits again the inspection of the coatings and the correction of flaws. Parts that are insufficiently covered may then be recoated and

this mode of creating the air, water, moisture, steam, oil, grease and in some respects also acid proof coatings for the preserving cans or containers guarantees a perfect sanitary preserving can or container after the various parts (the can body, the bottom and the top) are assembled and secured together with the adhesive binders that suit best for securing the seams (such as the side seams or overlapping end parts) and the top and bottom joints. It has been proposed already to make linings for boxes or vessels such as containers for milk etc. and to line the inner walls thereof with a foil of a suitable metal, such as, tin or aluminum and that foil is secured with an adhesive. Also in the present invention it is contemplated to have the interior side of the can or container covered with a metallic coating but the latter is of a character different from a foil since it is obtained by first applying a coating of varnish then powdering that coating with powdered metal, the so-called bronze, then by fluxing the areas covered with the powdered metal and finally by applying molten metal to the so fluxed powdered metal. This innovation has been claimed already in the application Serial No. 702,345 that was filed December 14, 1933, and of which division was required. The method of covering and the finished product covered with a layer of solid metal is claimed in my United States Patent No. 2,143,948 that was granted to me on January 17, 1939.

The innermost coating of the blank is, however, not limited to a single material and it will be a great simplification to simply coat the innermost side of the blank either the one for forming the can body wall or the lining with a solution of nitro-cellulose such as a lacquer of pyroxylin and in most cases a coating with a nitro-cellulose lacquer will suffice for preserving eatables and also beverages for a considerable period. This lacquer is even preferable to a coating of metal since it will not transmit the metallic taste to eatables and beverages.

The different materials for the coatings will be applied in a similar way by machinery of which a preferable system is shown.

Another improvement, disclosed by the present invention, consists of the can or container body having an inner wall and an outer wall and a packing of an economical material, as, for instance, asphalt, placed between the inner and outer wall and in addition reinforcing parts such as steel strips and wires or meshed steel strips or meshed or crosswise arranged wires laid in said packing. Fibres and dried grasses or weeds may

be even preferable to the steel strips and wires.

A further improvement consists also in creating a can body from a single blank and to wind it up in such fashion as to avoid a protuberance on the cylindrical outer surface of the can body which permits a close fitting of the bottom and top.

Another improvement consists also by employing the covering means that have been disclosed in my U. S. Patent No. 2,049,264 and to coat one of the sides thereof with nitro cellulose or with a solid layer of metal that has a base of varnish covered with powdered and fluxed metal. This innovation and improvement is especially adaptable when the tops and bottoms of the can or container are not covered on their interior sides with a layer of nitro-cellulose, or of a solid metal. The reason, for not covering the top or bottom with one of these coatings, may be that the material of which these tops and bottoms consist is too coarse or too porous.

Other advantages will be described in the now following detail description.

In the drawings forming part of the specification the—

Figure 1 represents one of the modifications of the preserving can in a sectional elevational view, showing the reinforcing steel strips placed in an oblique position.

Figure 2 shows on a reduced scale the single blank for making the can body of Figure 1 ready to be rolled into the shape of the can body and having therefore all the parts placed thereon that constitute that can body wall and having therefore also the coating applied to the part that forms then the innermost surface of that can body;

Figure 3 is a sectional view taken on the line 3—3 of Figure 1 but of the completed can body, showing thereby the arrangement with the overlapping portions of the blank;

Figure 4 shows a fraction of the can body wall with the reinforcing steel strips placed in a horizontal position;

Figure 5 shows a fraction of the can body wall with the reinforcing steel strips placed in a vertical position;

Figure 6 shows a fraction of the can body with the reinforcing steel strips arranged in a meshy fashion;

Figure 7 shows a fraction of the can body with the reinforcing parts formed of steel wires instead of steel strips and being arranged cross-wise.

Figure 8 shows a modification of the can body in a sectional view whereby two blanks (an inner and an outer) are used or two groups of paper layers with the packing and reinforcing wires or steel strips laid therebetween.

Figure 9 is a sectional enlarged view of a fraction of the can body having a special inner liner that is coated on its interior side with one of the preferable coatings and being secured to the inner wall of the can body by means of an adhesive coating that is either applied to that interior side of that inner wall or to the exterior side of the liner.

Figure 10 is a sectional view of a fraction of the can body, having a special inner liner which is coated on its interior side but being of the loose kind that does not adhere to the can body wall.

Figure 11 is a schematic representation of the layout on the sheet that is to receive the coating or coatings for the innermost can body walls

showing also the scheme for the simultaneous treatment of a number of the blanks which might be such of the special linings.

Figure 12 shows diagrammatically part of the machine and especially the mechanisms that serve for applying the coating of lacquer or of other suitable material to the areas of the large strips that will form the innermost wall of the can body such as diagrammatically illustrated in Figure 11 and including also the automatic mechanism that cuts the long sheet of paper into small sheets; a mechanism for printing on a label or the like to the side of the blanks that will form the outer side of the can, is also shown;

Figure 13 shows diagrammatically the additional mechanism that is necessary when a solid layer of metal is to cover the innermost wall of the can body and if desired also the outermost wall.

Referring more particularly to Figures 1, 2 and 3 the blank 1 consists of a single piece cut into a rectangular shape as shown in Figure 2. The blank itself may consist of a suitable kind of strongly compressed cardboard that does not need to be thicker than one thirty-second of an inch for cans that have to hold eatables. The first operation that then takes place is the coating of the area 2 of the blank with a suitable lacquer 3 that later forms the innermost wall of the can body. That area 2 may be covered with a suitable layer 4 of solid metal or that area may be covered with a coating of any equivalent material including resinous substances etc.

This procedure is preferably done right on the strip that is unwound from the large roll as it is delivered from the mill. Judging from Figure 2 it is therefore only about one-half of the whole blank that is thus to be covered with that layer or coating of lacquer or with solid metal etc. Considering that the width of the whole roll 10 as it comes from the mill and shown in Figure 11 permits five blanks 1 to be covered at once with the coating of nitro-cellulose lacquer etc. that coating is therefore applied before the single blanks are cut from the long sheet 11 that is unwound from the roll. The machine that prints the nitro-cellulose lacquer etc. to the area of five blanks imaginarily laid side by side as exemplified in Figure 11 is shown in Figure 12. This area is indicated by the lines to which point the arrows 12, 13, 14 and 15, shown in Figure 11

The same machine may have also the means that automatically cuts the sheet 11 in a transverse sense because the single blanks 1 may not be ready to be cut right away on account of the lacquer still being sticky. It is, however, possible to cut along the lines 16, 17 and to let the so-cut sheets dry, that are covered to about one-half with lacquer 3, until they may be placed in large numbers one upon the other without the danger that they will stick together when they will be compressed. Lots of fifty or more sheets may then be cut into the single blanks 1 along the imaginary lines 18, 19, 20, 21 and 22 and the single blank will be ready for the next operation. If the blanks are to be covered with some different equivalent solution the procedure is similar as exemplified in connection with the nitro cellulose lacquer but when the blanks must be covered in part with a layer of solid metal, such as tin, aluminum etc. there is a different machine needed. Both machines will be described subsequently.

Referring again to Figures 1, 2 and 3 and particularly to Figure 2 it will be noted that the re-

inforcing steel strips 23 are laid on the other half of the same side that is partly covered with lacquer 3. Before these reinforcing strips are laid on in the desired fashion there is a suitable packing material 24 of an adhesive character laid on that part of the side of the blank that is left free from the nitro cellulose lacquer 3. Although I do not wish to limit that material 24 to a single one I specify asphalt as one of the most economical ones that can be employed for that purpose. That layer of asphalt may be mixed with relatively fine sand and may be applied in hot condition or in a dissolved but thick sticky condition and this operation may be performed by machinery. The laying on of the reinforcing strips 23 may also be performed by machinery. The reinforcing strips 23 or the wires 25 become so embedded in the packing 24 that it will not be necessary to make a special layer of packing on top thereof. It will not be necessary to place the reinforcing steel strips in great regularity. At this stage the blank 1 is ready to be wound or compressed into the desirable shape. For making a cylindrical can body a mandrel 26 of that shape should be employed and the blank 1 rolled thereon whereby this operation must be started at the cut-end which is indicated by 16. While the blank is laid or wound around the mandrel 26 the inner wall of the body blank is thus obtained when the blank is wound up as far as indicated by the dotted line 27. From the imaginary line 27 towards the left there is still a part 28 left free from the packing 24 and the reinforcing steel strips 23 or wires 25.

This part 28 or a slice of it may be coated again separately or it might be dipped on with the solution that makes the nitro cellulose sticky when the blank is rolled up so that complete separation is obtained between the interior of the can and the packing 24. The cut edge 16 will also, at the same time, be dipped on with a lacquer of nitro cellulose so that no fibres are exposed to the interior of the can which would draw liquids into the walls. In order to obtain a flush outer surface of the can body the mandrel 26 has a recess that starts at the part where the cut end 16 of the blank 1 is to be engaged by that mandrel as shown in Figure 3.

This recess which has the depth of the thickness of the single blank sheet reaches as far as indicated by 29 where it is rounded outwardly and the remainder of the mandrel surface is then of the cylindrical shape. While that mandrel 26 continues in winding up the blank 1 there will be included the packing 24 and the reinforcing strips 23 or the wires 25 or the dried vegetable matter which will then be situated between the inner and the outer wall of the can body.

From Figure 3 it can be seen that the blank 1 makes a sharp outward bend at the point indicated by 30 and that the end 17 of that blank lies against that bend and that therethrough a perfect cylindrical outer surface of the can body is obtained. This is not only necessary for obtaining a harmonic exterior but it is important for permitting a perfect closure with the bottom and top piece. For increasing the hold of the bottom 5 and of the top 6 on the can body the top and bottom edges 7 and 8, respectively, of that can body, are either thickened or the corresponding part of the outermost convolution of card board or paper is bent somewhat outwardly as shown in Figure 1. The bottom is then suitably compressed on the lower end portion of the can body whereby a joint is obtained as shown in

Figure 1. The commodity may then be filled in and also the top may be secured in a similar way as explained in connection with the bottom. There may be also the covering means 31, 32 employed, as also exemplified in my United States Patent No. 2,049,264, and there may be another innovation in connection therewith which consists in folding up the outermost edge part of the covering means so that a part is created that lies against the corresponding inner side of the can body wall 2 and which is partly secured to that inner can body wall with a lacquer of nitro cellulose. This refers especially to the part of that covering means that reaches into the joint and which is then simultaneously compressed with the latter. For facilitating the removal of that covering means without the necessity of cutting it through, either that situated on the top end of the can or that situated on the interior side of the bottom, the part thereof indicated by 33, 34, respectively, is weakened considerably, that is, it is made much thinner than the remainder of that covering means, so that it will detach itself easily at that part when the center part 35 is gripped with the fingers and pulled outside of the can when the top 6 (or bottom) is removed or cut open.

Besides the nitro-cellulose which makes the border part of that covering means adhere to the can body wall, especially where the joint is formed, there is also another packing material employed for making the bottom piece (or the top piece) adhere to the corresponding part of the covering means that forms part of the joint. There are various materials employable for that last mentioned packing and one of the most economical is asphalt which may be applied in hot condition or in dissolved condition or both in hot and dissolved condition and that packing or sealing material will make the whole joint air, water, steam, moisture and acid proof while the nitro-cellulose on the covering means makes it also grease and oil proof. There may be a further innovation in connection with the covering means and it consists of coating (imprinting) the whole side either the interior side or the exterior side or both of that covering means with a layer of nitro-cellulose lacquer or with a layer of solid metal or with other materials dependent upon the character of the contents. If the latter are, for instance, of an oily or greasy character a solution of a resinous substance may suffice.

Preserves, such as eatables necessitate coatings that will not be dissolved by these preserves and these coatings should not have a disagreeable smell nor taste.

This is one of the reasons why a lacquer of nitro-cellulose would be preferable to many others and it has the advantage to lay on the surface of the paper without impregnating the latter which, however, is the case with most of other kinds, especially those that are soluble with turpentine.

By leaving then the part 33, 34 only slightly covered with the lacquer that is to constitute the part on which the covering means is to detach itself, as mentioned before, that part would then be weakened thereby. That weakened part could only be impregnated to prevent access of fungus etc. and besides it may be folded upon the part that adjoins the can body wall as shown in Figure 1 and an adhesive placed in that short folded part that simply holds the folded sections close against each other and thereby prevent also access of fungus etc. to the contents through the

less thickly lacquered or not lacquered parts 33, 34 (see strip 36 indicated by dotted lines). The adhesive in the folded part 33, 34 may consist of soft wax or paraffine or of a compound of other ingredients that are mixed with glycerine.

By applying a coating, as mentioned, on the interior or exterior side of the covering means 31, 32, no coating will then be necessary on the inner side of the top 6 and bottom 5 which, however, would be necessary if the covering means would be left out completely, or if the latter was not covered by a layer of lacquer or of solid metal etc.

If the can is to receive an angular shape such as of a cubic form or one with a rectangular, octagonal etc. sectional conformation or one that is of an oval sectional conformation, it is advantageous to make the cylindrical shape first and to compress the final shape by the use of mandrels or forms that possess the shape which the can is to receive.

For obtaining a close fitting of the top and bottom that portion of the overlapping part on the section 2 of the blank 1, that would hinder the top and bottom from being put on closely, may be cut out, as it is exemplified in Figure 2 by the cut out sections 46, 47 on the right side end corners of the blank 1. This scheme might apply also to such cans in which more than one body blanks are used, as for instance, with the can shown in section in Figure 8.

If not a special label is to be put around the can body there could be printed on, in one or even more colors, the label or other indicia that usually is customary with such containers or cans, and the printing operation could be performed before the particular part of the sheet 11 (see Figure 12) reaches the drum or cylinder 40 which applies the inner coating to the areas on the long sheet 11 that are limited by the borders 12, 13, 14 and 15 thereof.

Referring to the modification of Figure 8 that structure requires two blanks of which one, indicated by 37, constitutes the inner wall of the can body and the other, 38, the outer wall, and between these two walls is placed the packing 24 and the reinforcing steel strips 23 or the wires 25.

The ends of the inner wall blank 37 may overlap, as shown at 39, and so may also the ends of the outer wall blanks. The ends of the blanks may, however, not overlap and simply meet and in this instance a special strip of impregnated or lacquered paper may be pasted over the interstice that might be formed by the two ends of the blank that do not adjoin each other perfectly.

This would be necessary especially when it deals with the inner blank 37, because the contents, especially eatables, should not come into contact with the packing 24. In the case where the blank-ends do not overlap a better closure can be expected with the top and bottom. The arrangement may be made so that the meeting edges of the inner blank would be situated on a different part of the can body than the meeting edges of the outer blank and therefore the side seam or meeting edges of the inner blank may be situated on the opposite side of the meeting edges of the outer blank, such as exemplified in the drawings.

It is apparent that the scheme for coating the surface of the inner blank of the can, that is shown in section in Figure 8, must not differ from that described in connection with Figures 1, 2 and 3. The inner blanks of the can of Figure 8 would then simply be separated from those

parts of the sheets that are not covered with the coating of lacquer or of a solid metal or of any suitable material.

In case that the blanks 1, 37 and 38 for the can body are of an inferior material that is too porous for permitting the coating of them with a single layer of lacquer or of another of the mentioned materials it is then necessary to use a liner 41 or 42 of a suitable paper which will then be coated with the lacquer of nitro-cellulose or with solid metal or with any other of the materials suitable to the contents.

This liner, which is shown in section in Figures 9 and 10, may be secured again to the innermost wall of the blank 1 or 37 by means of a suitable adhesive binder, and such scheme is illustrated in Figure 9 in which the last mentioned binder is indicated by 43. The liner is then indicated by 41 and consists of a suitable kind of paper which might or might not be impregnated, or which might, or might not be of the type known as sulfite paper or parchment paper. The coating of its interior side is indicated by 45.

The inner liner may, however, not be secured to the inner wall of the blank 1 or 37, as shown in Figure 10, and in this instance the loose liner is indicated by 42. The latter should, however, at least, be sufficiently secured in the joints, together with the covering means, should the latter also be employed, and the ends of the liner, that are to form the side seam thereof, should overlap and should be secured to each other by means of nitro-cellulose lacquer and then compressed. The coating 45 of the liners 41 and 42 is also performed by machinery and in the method exemplified in Figure 12 whereby, however, the whole underside of the sheet will be covered by the lacquer or by the solid metal etc. whereby the printing operation will be eliminated which is simply obtained by letting the sheet pass at a little lower level than the level at which the sheet 11 moves and at the same time it will be necessary to stop the cylinders that constitute the printing mechanism of the machine. It necessitates, however, the change of the cylinder 40 for another cylinder that would have a correct and complete cylindrical shape.

Although the specific construction of the machines that are used for making the cans and containers which includes also the applying of the various coatings will be claimed in a special patent application that will be filed somewhat later than the present one, a brief description of the main parts of this machine will greatly help to comprehend the invention.

In Figure 12, the roll of paper is indicated by 18, 11 is the unwound sheet from that roll 56 indicates the cylinder that has a rubber blanket secured thereto upon which the black or color impression is made by the cylinder 51, 52 is the roller for rolling ink on the cylinder 51. 53 is a cylindrical body for evening and spreading the ink on the slab 54 and for providing the roller 52 with a certain amount of ink. 55 is a cylinder for exerting counterpressure to the cylinder 53 and thereby cause the impression on top of the unwound sheet 11. 56 and 57 are displaceable rollers for keeping the unwound sheet at a lower level should no printing take place which is the case when the inner lining 41 or 42 is to be covered with the coat of nitro-cellulose etc. in which case the roll 18 of card board must then be substituted by a roll of paper whose quality and thickness suits best for the lining 41 or 42.

The cylinder 55 is also displaceable and can be lowered simultaneously with the rollers 56, 57.

The printing on of the label or of other matter may, however, be performed on the sheets that are cut already along the imaginary lines 16-17, as indicated in Figure 11, after the coating, on the area that is limited by the lines 12, 13, 14 and 15, has completely dried. Since five labels can be printed thereon at once they may be alike or each may be of a different design and accordingly each may serve for indicating the particular commodity that is to be contained in the can. There may be, however, far more than five blanks or less than five obtainable from the area that is limited by the boarders of the sheet 11 and the cut edges 16, 17, all dependent upon the width of the sheet 11.

The function of applying the lacquer or other coating, with the exception of the metallic coating, is performed by the drum 40. This drum is not of a perfect cylindrical design because it has the protuberances 58 which are so positioned on the cylindrical surface of that drum, that the moving sheet 11 will be heavily contacted by them, that is, imprinted, while the drum is also revolved in the sense indicated by the arrow 59. Each protuberance 58 has therefore a curved surface of the size that equals that of the area that is limited by the lines 12, 13, 14 and 15 as indicated in Figure 11. Each of these protuberances must also be correctly distanced from each other and must correspond otherwise with the positions of the areas that must be covered by the coatings on the unwound sheet 11. For exerting a certain counter pressure to the protuberances 58, in order to obtain a good contact of the sheet 11 with them, there is a cylinder 60 employed that is sustained by springs 61 that bear against the bearings of that cylinder. The cylinder 60, not being very heavy, is then lifted a little against the tension of the spring 61 every time one of the protuberances 58 engages the sheet 11 underneath that cylinder 60. Underneath the drum 40 there is a moistener arranged that consists of a rubber or the like broad belt 62 whose lowermost part is immersed in a tank 63 that contains the dissolved lacquer or other liquid that serves for making the coating 3 on the sheet 11, or 45 on the linings 42, 43.

The innermost surface of that belt 62 may be dentated to permit a dentated wheel 64 to mesh with the teeth on the inner side of that belt and to keep the latter in continuous movement so that lacquer or other liquid will be continuously brought from the tank 63 to the uppermost part of the belt 62 and thus be transferred to the surfaces of the protuberances 58 which latter imprint it again to the sheet 11. The dentated wheel 64 is therefore so arranged that it will hold the belt 62 in the proper position for engagement with the protuberances 58. The outer surface of the belt 62 may be made porous or it may be simply roughened somewhat to permit better adherence of the lacquer or other liquid to that surface.

The sheet 11, after having received its impressions of lacquer, etc., reaches the cylinders or rollers 65, 66 which serve for holding the sheet 11 only on its two outer marginal spaces 67, 68 (see Figure 11). The still wet coating on the sheet 11 will therefore not be touched by these rollers. Right after having passed between the cylinders or rollers 65, 66 the sheet 11 may be cut into single sheets by means of the knife 69 which is so adjusted by mechanism that it as-

cends and cuts the sheet 11 along the imaginary line 16 in the fashion of a shear. The other shear blade 70 may be stationary.

The knife 69 may be actuated by a mechanism that comprises a lever 71 that is so positioned that it will be engaged by the front edge of the protuberance 58 that encounters it and it will be pushed sufficiently thereby so as to actuate a rod 72 which in turn moves the lever 73 to which the rod 72 is pivoted. The lever 73, being secured to a dentated wheel 74 which is mounted on a shaft, causes that dentated wheel to partly rotate on that shaft, and since that dentated wheel meshes with the teeth of the rack 75, to which the knife 69 is secured, the latter, together with the rack 75, is thereby moved upward, and the blade of the knife 69 comes thereby into engagement with the blade 70 every time in which the frontal edge of any of the protuberances 58 engages the lever 71. By taking the correct distance from the front edge of one of the protuberances 58 to the front edge of the next one and by adding that distance one or several times to the sheet 11 starting at the point where the lever 71 will be first engaged by the front edge of any one of the protuberances 58 the correct place will be found thereby on which the knife 69 must cut the sheet.

According to the sizes of the cans the drum 40 must vary and so must also vary the distance on which the knife 69 has to cut the sheet 11. The rod 72 and other parts of that mechanism must, therefore be adjustable to any size of cans. It is therefore advisable to make the rod 72 sufficiently long and to provide a screw to the pivot 75 for permitting the securing of the latter to any part of the rod 72.

The weight of the rack 75 causes the latter together with the knife 69 to descend as soon as the protuberance 58 that pushed the lever 71 does not hinder the latter anymore from moving again in the path of the front edge of the next following protuberance 58. The falling single cut sheets are caught by a pair of arms 77 which hold each sheet so that it turns over and then lays on a moving rack 78 that goes in the direction of the arrow 79. The single sheets may be laid out and allowed to dry before they are cut into the single blanks 1 or before any printing is made to the back thereof which will then be later the outer side of the can, should the printing not have been done before.

If the innermost side of the can shall receive a coating of solid metal then the procedure needs some additional machinery and the uncut sheet 11 will be directed towards those additional parts. The direction which the sheet will then take is indicated by the dotted line 80 and in Figure 13 are shown, in a diagrammatic way, the additional main parts of the machine.

If the innermost wall of the blank 1 is to receive a solid layer of metal the first coating of that area may consist of varnish instead of lacquer. The sheet strip 11 is then directed towards the cylinder 81 that has a suitable soft dry cloth 82 wound around the cylindrical surface of that cylinder and that dry cloth 82 takes up powdered metal, the so-called bronze, that is contained in the trough 83. The bronze that sticks to that dry cloth 82 will readily be transferred to the varnished or lacquered areas on the sheet 11 while that sheet is moved along and the cylinder 81 revolves. There is another cylinder 84 employed that acts as a duster for removing the surplus bronze that sticks to the sheet 11.

This cylinder 84 may turn faster than the others and the cloth 85 that is wound around its cylindrical surface will be shaken free from the bronze that adheres to it when it will be engaged by the sticks 86 that are so agitated that they will continuously hit that cloth.

Both the bronzing unit and the dusting unit may be sufficiently encased for preventing the bronze from floating in the air and settling on other surfaces of the sheet 11.

The next cylinder which engages the sheet 11 is indicated by 87 and serves for fluxing the areas that are varnished and then powdered with bronze. The flux is contained in the trough 88, and while the cylinder 87 revolves its cylindrical surface will be moistened by the flux, that is of the dissolved kind, and consequently the under surface of the sheet 11 will thus be wetted therewith. The bronzed areas on the sheet 11, that are thus fluxed, are then ready to be covered by a thin layer of solid metal. The latter may be tin or aluminum when it deals with eatables while other metals may be employed for other commodities.

The molten metal is contained in the trough 90 of graphite and is kept there fluent by the heat applied through the flame 91. The drum 92, which may be of the same shape as the drum 40 and therefore may have also protuberances 93, is so adjusted that the protuberances will dip into the molten metal container in the trough 90 and while the drum revolves the protuberances successively apply the relatively thin layer of metal, that sticks then to the surfaces of these protuberances, to the bronzed and fluxed areas on the sheet 11 while that sheet is moved along.

After the molten metal is applied to the sheet 11 the latter may be cut into the single sheets by means of the same or by a similar mechanism that has been described previously and which includes the parts indicated by 71 to 79, inclusive. Obviously, also the cylinders 81, 84 and 87 may be of the same general construction as the drum 92 and the protuberances on these cylinders or drums must be so adjusted as to bronze, that is, apply the powdered metal, dust and flux, respectively, only the areas on the sheet 11 that received the imprint with varnish or lacquer by the protuberances on the drum 40.

The first cut sheets which are those that still contain five single blanks, as shown in Figure 11, may be printed on on those parts of the back thereof that will form the outer side of the can body, should the printing operation not have been performed previously. The single blanks 1 may then be cut from that sheet and each blank will then be ready for being rolled into the can body as previously explained.

It might be desirable to have also a metallic coating on the outer side of the can body for practical, as well, as, decorative purposes and that coating would not need to be of a metal that, like the one used for the innermost side, is of a non-detrimental character to the contents and therefore to the health of the consumer. It is, as well, not necessary to make that coating of solid metal. It might, for instance, be of a highly decorative effect to cover the outer side of the can body with bronze, either with so-called silver or gold bronze, and to emboss or add solid metal in form of a suitable design, lettering etc., on top of the flat bronze, layer whereby that solid metal may be of a different metal than the bronze, for obtaining contrasty effects. That part 75

of the machine is also shown, in a diagrammatic way, with the larger cylinder or drums, shown only in fraction. The drum 95 would then serve for imprinting the varnish on the area 5 of the sheet 11 that will be the outermost side of the can body. In construction it will be like the drum 40 and besides having a trough, similar to that indicated by 63, there may be additional parts used in connection therewith, as, for instance, a belt and an additional dentated wheel like those indicated by 62, 64, respectively.

The drum 96 may then serve for powdering the varnished areas with the chosen bronze, whereby those parts will be left free from the bronze that 15 are not varnished. The bronzing drum 96 has therefore also similar protuberances as the drum 95. The dusting wheel or cylinder 97, that is the next that engages the mentioned area of the sheet 11, may be completely cylindrical and so 20 may be the drum 98 that serves for fluxing the bronzed parts. This drum, however, may have also protuberances, so that only the varnished and bronzed areas will receive a slight coating of flux, and finally the drum 99 is to be used 25 which may only emboss the outer wall of the can body or which may apply a layer of solid metal, either entirely or in form of a design or lettering, on the bronzed area. If the latter addition is to be made there must then be such 30 additions to the drum 99 that cover the imprinting parts on the protuberances of that drum with the chosen molten metal. A similar arrangement will then be necessary as indicated by the reference numerals 90 and 91 in connection 35 with the drum 92.

In many instances it is preferable to use other materials than those of metal for the reinforcing parts in the can body wall. The most adaptable would be those of a fibrous character 40 which includes grasses and weeds of many specimens of which the whole plant could be taken with the exception of the roots and then compressed and dried. There might, however, only be used the fibres of the stems and branches while 45 the leaves will be discarded. Jute fibres would, for instance, be very useful. The fibres or dried grasses etc. might be laid on the packing in the manner that was disclosed in connection with the steel strips 23 and wires 25, as shown in 50 Figures 2, 4, 5, 6 and 7, and the fibres or grasses etc. could be made into small bundles and cut to the correct size.

Some of the domestic plants or fibres that are abundant and which can be used for the aforesaid purpose are straw, sea grass and prairie grass, the fibres of ragweed and of other weeds, that usually have no other usefulness nor beautifying properties. In dried condition and surrounded by the packing, these plants or fibres 60 thereof preserve their tough character and add greatly in strengthening the can body wall.

A can made of the materials mentioned will not rust and is also in this respect superior to cans made of sheet metal.

If the can or container blank 1 or 38 will not be printed on, so that a special label will be put around the container body when the can or container is completely finished and the eatables or other commodity is filled in, the outer surfaces 65 of that can or container should be made non-impregnable, especially to moisture, water, steam and other influences, especially of the atmospheric air. The filled in and closed can might then be covered with paint or lacquer and in this instance it simply might be dipped in the liquid

paint or lacquer etc. and the surplus, sticking to it, allowed to drain off, whereby the label may be affixed while the paint or lacquer is not completely dry so that the label will stick to the outer side of the can or container.

I have obtained a very economical as well as practical coating for the outer side of the can by dissolving asphalt in gasoline and by applying the so obtained fairly thick solution to the outer side of the can body. The so obtained coating is of a deep black with high lustre when dry, which adds to the good outer appearance of the can or container and which is at the same time water, moisture steam and acid repellent.

It is also contemplated to use the metallic strips or wires simultaneously with fibres whereby a specially strong and resistant can or container body wall will be obtained thereby.

What is claimed is:

1. In a sanitary preserving can or container constituted in part by a can body with inner and outer walls that consist of a material in blank form that is wound up into the can body, the innermost side of that can body imprinted with a coating of material that is adapted to preserve the contents from fungus and other influences from the non-sterilized air, and all the other parts of that can or container that form part of the innermost side thereof also imprinted with the same material that coats the innermost side 25 of the wall of the can body, and a packing between said inner and outer walls of the can body having metallic narrow parts and dried vegetable matter embedded therein for reinforcing purposes.

2. In a sanitary preserving can or container constituted in part by a can body with inner and outer walls made from fibrous material, both the inner and outer walls formed by a single blank that is wound into said can body, the area forming the innermost side of that can body imprinted with a layer of air, water, oil and grease proof material that is applied to said blank before its formation into the can body thus permitting close and easy inspection of the coating before 45 the can body is finished.

3. In a sanitary preserving can or container consisting of a can body, top and bottom, the can body constituted by fibrous blank material with packing and reinforcing steel strips or wires, the inner side of that can body coated with a layer of lacquer of nitro-cellulose and that lacquer applied to said fibrous blank material before the fibrous blank material is formed into the can body.

10 4. A sealed sanitary preserving can or container consisting of the can body, the top and the bottom and all constituted in part of fibrous material, the can body consisting in part of wound up fibrous sheets, a material, tasteless and odorless when dry, forming the innermost surface of the can or container and being directly contacted by the contents thereof, said material adapted to protect the contents from outside influences, such as fungus, water, air, oil grease, steam, moisture and acids, said material applied to the innermost side of the innermost situated fibrous material of the can body, top and bottom while this fibrous material is still in sheet form and before the forming of the can or container, for permitting close inspection of the coated parts and the eventual recoating of flaws.

15 5. A sealed sanitary preserving can or container consisting of the can body, the top and the bottom and all constituted in part of fibrous material, the can body consisting in part of wound up fibrous sheets, a material, tasteless and odorless when dry, forming the innermost surface of the can or container and being directly contacted by the contents thereof, said material adapted to 20 protect the contents from outside influences, such as, fungus, water, air, oil, grease steam, moisture and acids, said material printed to one side of the fibrous material while the latter is still in sheet form and the printed on side forming the innermost side of the can body, top and bottom, when the can or container will be formed, thus permitting close inspection of the imprinted parts and the correcting of them before the can or container is assembled and formed.

HEINRICH KARL.
